(57) **CLAIM**

The ornamental design for osteosynthesis clip features, as shown and described.

DESCRIPTION

FIG. 1 is a top perspective view of osteosynthesis clip features;

FIG. 2 is a bottom perspective view of the osteosynthesis clip features of FIG. 1;

FIG. 3 is a front view of the osteosynthesis clip features of FIG. 1;

FIG. 4 is a back view of the osteosynthesis clip features of FIG. 1;

FIG. 5 is a left view of the osteosynthesis clip features of FIG. 1;

FIG. 6 is a right view of the osteosynthesis clip features of FIG. 1;

FIG. 7 is a top view of the osteosynthesis clip features of FIG. 1;

FIG. 8 is a bottom view of the osteosynthesis features clip of FIG. 1;

FIG. 9 is a top perspective view of another set of osteosynthesis clip features;

FIG. 10 is a bottom perspective view of the osteosynthesis clip features of FIG. 9;

FIG. 11 is a front view of the osteosynthesis clip features of FIG. 9;

FIG. 12 is a back view of the osteosynthesis clip features of FIG. 9;

FIG. 13 is a left view of the osteosynthesis clip features of FIG. 9;

FIG. 14 is a right view of the osteosynthesis clip features of FIG. 9;

FIG. 15 is a top view of the osteosynthesis clip features of FIG. 9; and,

FIG. 16 is a bottom view of the osteosynthesis clip features of FIG. 9.

(Continued)

In the drawings, the broken lines depict environmental subject matter only and form no part of the claimed design.

1 Claim, 12 Drawing Sheets
